UNITED STATES PATENT OFFICE.

THOMAS FAGAN, OF LONDON, ENGLAND.

APPARATUS FOR PLAYING GAMES.

Application filed May 19, 1928, Serial No. 279,136, and in Great Britain May 28, 1927.

The invention relates to apparatus for playing games and has for its object to provide a device whereby a game may be played in which some amount of skill will be required and a considerable amount of uncertainty or chance will be present.

Broadly, apparatus according to this invention consists in mounting a number of movable pieces arranged behind each other and each bearing an appropriate symbol, number or letter, etc., upon means which can be operated so as to bring said pieces successively past a point of observation until the movement of said means is arrested, means being provided whereby the movement of the said pieces can only be arrested with one of said pieces lying properly in the point of observation.

For the purpose of the invention a predetermined number of plates, cards or the like, hereinafter referred to as cards, formed of any suitable material may be employed, each card bearing preferably on each side thereof a marking or markings such for example as part of a number, playing card, symbol or the like and these cards are mounted and so marked that when two or more thereof are exposed to view in the same plane in an edge to edge position a complete number, playing card or symbol or the like will be displayed and means are provided for "shuffling," changing or turning over such cards in such manner that it is uncertain which thereof will be displayed.

For example, said cards may be pivotally mounted by one edge thereof between discs carried by a spindle mounted in or on any suitable frame. Said discs may be provided with perforations adjacent the peripheries thereof and the cards may be furnished with pins or projections engaging in said perforations so that said cards are thus pivotally mounted at a point adjacent the edges of said discs or instead of being mounted between discs said cards may be mounted in a frame or otherwise.

The said spindle is preferably mounted with capability of freely rotating and is preferably furnished with a fly or loaded wheel which is fixed thereon and means are provided for rotating the spindle and allowing the same to run freely, the arrangement being such that the momentum of the fly or loaded wheel will cause the spindle and discs, to rotate and the pivotally mounted cards to turn about their pivots and change their

faces until the momentum of said fly or loaded wheel or the like has been expended thus the particular pair of cards for the time being exposed to view is uncertain depending upon when said wheel stops.

In order that only one complete number, playing card, symbol or the like may be exposed to view at one time a suitable resilient or other finger or other means is provided adapted to slightly retard or brake said cards in their pivotal movement whilst each card is marked on the back with one half of the number, playing cards, symbol or the like whilst the other half required to complete such marking is carried by the front surface of the card following it so that when said back is exposed in juxtaposition to the following front of a card a complete number, playing card, symbol or the like is displayed.

Any suitable means may be employed for imparting motion to the said spindle such as for example ratchet or equivalent mechanism which may be hand operated or any suitable motor such as an electric or a clockwork or other motor may be employed for the purpose in view. Any suitable means may also be provided for suddenly stopping the rotation of the spindle of the apparatus at random at any desired moment as will be readily understood.

If desired several series of such cards, or the like may be so mounted upon the one spindle and such series may be connected or not with one another and the movement of one series might be dependent upon the movement of the other, by any suitable means. The flywheel or flywheels may be coupled to the spindle through suitable gearing and/or a suitable frictional clutch which will permit the relative position to alter or be altered from time to time.

The whole apparatus may be enclosed in a box or case having a window at which the cards may be displayed and means may be provided upon the exterior of said box or case for setting the apparatus in motion.

The apparatus may be employed for playing any suitable game and each card may be marked to represent half a number or playing card, or it may be marked with part of any other sign or symbol or letters of the alphabet or signs of the zodiac and the apparatus may be employed in the game of telling fortunes or as a race game or foretelling the results of horse races.

In order that my invention may be clearly

understood and readily carried into effect, I have appended hereto a sheet of drawings illustrating two embodiments of same, and wherein:—

5 Fig. 1 is a front elevation of one form.

Fig. 2 is a sectional front elevation taken through the spindle to which the card or the like carrying frames are attached.

10 Fig. 3 is a side elevation half in section showing the mounting of the card carrying members.

Fig. 4 is a part sectional front elevation showing a slight modification, and

15 Fig. 5 shows a suitable method of attaching the card carrying members to the rotary discs.

Referring to the drawings I have shown the invention as applied to a device for cutting a pack of cards in which by the rotation 20 of a spindle 1 a number of card-like pieces 2 are successively brought in a plane which will expose each card piece 2 through an opening 3 in a suitable casing 4 accommodating the pieces 2. It is desired to ensure that during 25 the rotation of the spindle 1 the exposure of each card will only be momentary until the rotation of the spindle is arrested, when two pieces will be held in a common vertical plane, one beneath the axis of the spindle 1 and one 30 above said axis as indicated at 2^a and 2^b respectively in the drawings. The size of the opening 3 can be such as to expose both of the said pieces or only one, and if both are exposed the pieces 2 can be so arranged that 35 each exposed pair of pieces combine to make one symbol etc. to be exposed. For instance each piece 2 can be half a playing card, the opposing faces of a pair of pieces lying next to each other being complementary to each other. If desired each piece can be a complete card or other symbol carrying member.

The pieces 2 are mounted so that they travel each with one surface foremost towards and away from the opening 3 in the direction of the arrow in Fig. 3, the pieces lying behind each other. This can be effected by mounting each piece 2 in a transverse folded or channel section strip 5, a number of which are provided each having its ends fairly loosely engaged in circular openings 7 in a pair of discs 6 fixed on the ends of a hub member 8 fixed to the spindle 1. For this purpose nuts 9 may be threaded on to the threaded ends 10 of the hub member 8 and the discs 6 interposed between these nuts and annular parts adjacent the ends of the hub member 8. Alternatively, as in Fig. 4, the discs 6 may be secured to the inner faces of a pair of fly wheels 11 by means of screws 12 passed through the discs 6 into the fly wheels which are engaged over the reduced ends of the hub member 8. The fly wheels 11 can serve as a suitable means of obtaining the requisite momentum for rotating the spindle 1 at the speed required to carry the pieces 2 quickly

past the opening 3, the spindle 1 being mounted in suitable bearings 13 and provided at its ends with knurled caps 14 for engagement by an operator. This arrangement obscures the flywheels 11, but if desired the said 70 flywheels can be outside the casing 4, for instance by taking the place of the caps 14, the discs 6 in this event being arranged as shown in Fig. 2. Instead of two flywheels 11 only one need be employed for instance as shown 75 at 15 in Fig. 2.

The pieces 2 engage a resilient finger 16, which can be a curved leaf spring, during their movement, and the free end of this leaf spring which engages the pieces is so positioned that when the rotation of the spindle 1 is arrested the outer end of one of the pieces (i.e. 2^b) will be held against the finger and will lie in substantially the same plane as the piece immediately preceding it (i.e. the piece 80 2^a), the inner ends of the said two pieces lying very close to each other as shown in Fig. 1. This finger 16 may be made adjustable.

The channel or folded strips 5 carrying the pieces 2 have radiused edges 5^a so that they turn easily in the apertures 7, and upstanding lugs 5^b are preferably formed on the said strips for gripping the pieces 2. The pieces 2 will travel more easily past the finger 16 if only one free edge of the pieces is actually 95 engaged with the finger as it passes the finger. For instance it might be desirable to arrange two pieces 2 in each member 5, as shown in Fig. 5, particularly when employing a pack 100 of cards, and in this event I so arrange each pair of pieces in a member 5 that their free or outermost edges slightly overlap as indicated at 2^c in Fig. 3, the front piece extending beyond the rear piece. The channel pieces 5 may be separate corner pieces fitted 105 to each edge of the cards, omitting the cross strip. This will permit damaged cards to be replaced by flexing the cards to engage the pivots 5^a in the holes 7 of the discs 6.

The appliance may of course be worked by 110 clockwork or other alternative means, and a window may be provided in the opening 3 provided it clears the free ends of the pieces 2.

I claim:—

1. Apparatus for playing games comprising a rotary structure, a number of sign-bearing plates arranged behind each other and each pivotally mounted at one end upon the rotary structure and free at its other end, and a projection located in the path of travel 115 of the plates, arranged successively to engage the free ends thereof and positioned so that when movement of the plate assembly is arrested the plate engaging the projection will have an exposed surface.

2. Apparatus for playing games comprising a rotary plate-carrying structure, an arresting stop, a plurality of sign-bearing plates pivotally carried by the rotary structure having free ends successively engaging the ar- 130

resting stop when in upstanding position during rotation of the structure, and falling by gravity on disengagement with said stop, the position of the stop being such that the last 5 plate to fall by gravity on leaving the stop, lies in the same vertical plane as the next plate which is held upstanding by the stop, and forms part of an exposed surface the other 10 complementary part of which is the stop-engaged plate.

3. Apparatus for playing games comprising a casing, an axially rotatable hub member mounted in bearings in the casing and including two spaced-apart discs, a circumferential row of apertures in each of said discs, plate-holders, each supported by the two discs and pivotally mounted in the apertures thereof, a plurality of sign-bearing plates held by their inner edges in the plate holders, and an arresting stop successively engaging the free edges of the plates on rotation of the hub to retain the plate engaged by it in upstanding position, each plate on leaving the stop falling by gravity.

25 4. Apparatus for playing games comprising an apertured casing, an axially rotatable hub member mounted in bearings in the casing and including two spaced-apart discs and one or more flywheels, a circumferential row 30 of apertures in each of the discs, plate-holders each supported in the two discs and pivot-

ally mounted in the apertures thereof, a plurality of sign-bearing plates held by their inner edges in the plate holders, and a resilient arresting finger successively engaging the 35 free edges of the plates on rotation of the hub to retain the plate engaged by it in upstanding exposed position, each plate on leaving the said finger falling by gravity to constitute part of an exposed surface visible 40 through the casing aperture the complementary part of which is constituted by the stop-engaged plate.

5. Apparatus for playing games comprising a casing, an axially rotatable hub member mounted in bearings in the casing and including two spaced-apart discs and one or more flywheels, a circumferential row of apertures in each of the discs, channel-section plate-holders each supported in the two 50 discs and having their ends pivotally mounted in the apertures thereof and adapted to receive in their channels the inner edges of sign-bearing plates, and a resilient finger adapted, on rotation of the hub, to successively engage the free outer edges of plates fitted in said holders, and positioned to retain a plate engaged by it in the same plane as the last plate which has passed said finger, when rotary movement of the hub is arrested.

THOMAS FAGAN.
